(57) **CLAIM**

The ornamental design for a robot toy, as shown and described.

DESCRIPTION

FIG. 1 is a front perspective view of a robot toy according to the present invention.

FIG. 2 is a rear perspective view of the robot toy illustrated in FIG. 1.

FIG. 3 is a front elevation view of the robot toy illustrated in FIG. 1.

FIG. 4 is a rear elevation view of the robot toy illustrated in FIG. 1.

FIG. 5 is a side elevation view of the robot toy illustrated in FIG. 1.

FIG. 6 is another side elevation view of the robot toy illustrated in FIG. 1.

FIG. 7 is a top plan view of the robot toy illustrated in FIG. 1; and,

FIG. 8 is a bottom plan view of the robot toy illustrated in FIG. 1.

The broken lines in the figures of the robot toy are for the purpose of illustrating portions of the article that form no part of the claimed design.
